GAS OPERATED PLUMBER'S HELPER

Delmar C. Steinwedel, Seymour, Ind., assignor to Seymour Tool & Engineering Co., Inc., Seymour, Ind., a corporation of Indiana

Filed Feb. 7, 1963, Ser. No. 73,474

Term of patent 14 years

(Cl. D9—2)

FIG. 1 is a view of a gas operated plumber's helper showing my new invention;

FIG. 2 is a side elevational view thereof;

FIG. 3 is a rear elevational view;

FIG. 4 is a front elevational view;

FIG. 5 is a top plan view; and

FIG. 6 is a bottom plan view thereof.

I claim:

The ornamental design for a gas operated plumber's helper, substantially as shown.
